UNITED STATES PATENT OFFICE.

OTTO SEELHORST, OF PHILADELPHIA, PENNSYLVANIA.

DESIGN FOR A PUZZLE-BOARD.

SPECIFICATION forming part of Design No. 28,774, dated May 31, 1898.

Application filed April 14, 1898. Serial No. 677,629. Term of patent 7 years.

To all whom it may concern:

Be it known that I, OTTO SEELHORST, a citizen of the United States, residing in the city and county of Philadelphia, State of Pennsylvania, have invented and produced a new and original Design for a Puzzle-Board, of which the following is a specification, reference being had to the accompanying drawings, forming part thereof.

- o The leading feature of my design for a puzzle-board is a field formed of sections of geometrical form, some having shaded and others plain surfaces and which when assembled form a flag.
- 5 5 Figure 1 represents a plan view of a puzzle-board embodying my design. Fig. 2 represents a section thereof on line α α , Fig. 1.

In the drawings, A designates a puzzle-board formed of the sections B, C, D, E, F, G, o H, J, K, L, M, N, P, and Q, said sections be-

ing of various geometric forms, some of which are triangular, others rhomboidal, others trapezoidal, and one rectangular. Some of the sections have plain faces, as at R, and others have plain and shaded faces, as at S T. 25 The sections P and Q have entirely-shaded faces, as at U. The section B has a shaded face, as at V, and a star W thereon.

The puzzle-board thus embraces a triangular field and parallel stripes, the latter extending from the two sides X Y of said field. 30

Having thus described my invention, what I claim as new, and desire to secure by Letters Patent, is—

The design for a puzzle-board, substantially 35 as described and shown.

OTTO SEELHORST.
